HOLDING DEVICE FOR IRONING BOARD COVERS

Filed March 24, 1928

UNITED STATES PATENT OFFICE

JOSEPH H. DAYTON, OF LOS ANGELES, CALIFORNIA

HOLDING DEVICE FOR IRONING-BOARD COVERS

Application filed March 24, 1928. Serial No. 264,555.

My invention relates to and has for a purpose the provision of an extremely simple, substantial and inexpensive holding device particularly adapted, although not necessarily 5 for use on ironing boards, and by which a cloth or other form of covering for an ironing board can be securely held thereon against displacement and in a taut condition so that the covering will present a smooth surface for 10 ironing operations.

It is a further purpose of my invention to provide a holding device of the above described character including members engageable with the ironing board covering on the 15 side edges of the board and connected in a manner to firmly clamp the covering on the board, the device being adjustable to hold coverings on boards of various widths and on boards having parallel sides or relatively 20 inclined sides with equal facility and effectiveness.

I will describe only one form of holding device for ironing board covers embodying my invention and will then point out the 25 novel features in claims.

In the accompanying drawing,

Fig. 1 is a view showing in bottom plan an ironing board with a number of the holding devices embodied in my invention applied 30 thereto to hold the covering thereon;

Fig. 2 is an enlarged sectional view taken on the line 2—2 of Fig. 1 and looking in the direction of the arrows;

Fig. 3 is a perspective view of the holding 35 device;

Figs. 4, 5, and 6 are fragmentary views illustrating the manner in which the holding device is adjustable to hold coverings on ironing boards of different widths; and

40 Figs. 7 and 8 are fragmentary views illustrating the manner in which the device is adjustable to effectively hold coverings on ironing boards having relatively inclined sides.

Referring specifically to the drawing in 45 which similar reference characters designate similar parts in each of the several views, my invention in its present embodiment comprises a pair of members M and M' of identical construction, and in the present instance 50 each of the members is constructed of a single

length of stiff wire bent between its ends into the form of a V to provide a pair of arms 10 and 11 and a connecting bight 12.

The free ends of the arms are bent laterally to one and the same side of the arms to provide extensions 13 having inclined portions 14 and right angularly disposed portions 15. The extremities of the extensions 13 are bent and pointed as at 16 to provide hooks 17, and in the use of the device the extensions 13 constitute cover engaging and gripping portions of the members. One of the arms 10 is coiled upon itself intermediate its ends to provide an eye 18 disposed flatwise between and substantially in the plane of 60 the arms.

The members M and M' are resiliently connected by means of a coiled expansible spring S having its ends bent to provide closed loops 19 through which the wire of which the members are constructed can pass freely. By shifting the position of the spring S on the members M and M' to engage the loops 19 of the spring with the bights 12 and 12^a of the members as shown 70 in Fig. 6, or with the eyes 18 and 18^a of the members as shown in Fig. 4, or with the eye of one member and the bight of the other member as shown in Fig. 5, it will be clear 75 that the device is rendered adjustable to vary its overall length so that it can be applied to ironing boards of different widths.

A number of devices as above described are employed at intervals along the length of an ironing board B to hold the usual cloth or 80 other suitable covering C thereon as is shown in Fig. 1. In applying one of the devices, the covering C is first placed upon the board and its sides lapped over the side edges of the board. The extensions of one of the members M or M' are now hooked over one side edge of the board and the spring S adjusted 85 on the members so that when the extensions 13 of the other member are hooked over the other side edge of the board, the spring will be placed under tension and will thus urge the members towards each other to cause the hooks 17 of the extensions 13 to bite into the covering C and thereby securely clamp the covering against displacement on the board. 90

An important feature of my invention results from the provision of the relatively large circular eyes 18 and 18^a, as it will be clear that when the spring S is adjusted to engage its ends with the eyes and the device is applied to an ironing board having tapered or relatively inclined sides as shown in Figs. 7 and 8, the ends of the spring are free to shift laterally and around the eyes, and the members M and M' to rock freely about the points of engagement of their eyes 18 and 18^a, with the spring, so that the tension of the spring will be exerted equally upon all of the hooks 17 and 17^a, thus insuring that all the hooks will be equally effective in their holding action. This self-equalizing function is also present to a lesser degree when the ends of the spring are engaging the bights 12 and 12^a of the members as the spring ends are free to shift laterally in the bights and the members to rock freely about the points of engagement of their bights with the spring.

Although I have herein shown and described only one form of holding device for ironing board covers embodying my invention, it is to be understood that various changes and modifications may be made therein without departing from the spirit of the invention and the spirit and scope of the appended claims.

I claim:

1. As an article of manufacture, a pair of members, each comprising a pair of arms connected at one of their ends to form a bight and spaced apart at their other ends, extensions projecting laterally from the other ends of the arms and having hooked portions, an eye intermediate the ends of the arms and disposed substantially flatwise and between the latter, and resilient means movably connected to the members and capable of being shifted to connect the bights of the members, or the eyes of the members, or the bight of one member with the eye of the other member.

2. As an article of manufacture, a pair of members, each comprising a pair of arms connected at one of their ends to form a bight and diverging towards their other ends to form a V, extensions projecting laterally from the other ends and to one and the same side of the arms, the extensions having hooked extremities, an eye intermediate the ends of the arms and disposed substantially flatwise and between the arms, and a coiled expansible spring connected at its ends to the members and shiftable to engage its ends with the bights formed at the juncture of the arms of the members, or the eyes of the members, or the bight of one member and the eye of the other member.

3. As an article of manufacture, a pair of members each of which is constructed from a single length of wire bent between its ends

into the form of a V to provide a pair of arms and a connecting bight, the free ends of the arms being bent laterally to one and the same side thereof to form substantially right angular extensions having their extremities bent to form hooks, one of the arms being curled upon itself intermediate its ends to provide an eye between and substantially in the plane of the arms, and a coiled expansible spring connected at its ends to the members and shiftable to engage its ends with the bights of the members, or the eyes of the members, or the bight of one member and the eye of the other member.

4. In a holding device of the character described, a member comprising a pair of arms connected at one of their ends to form a bight and spaced apart at their other ends, lateral extensions on said other ends of the arms, and an eye intermediate the ends of the arms.

5. In a holding device of the character described, a member comprising a pair of arms connected at one of their ends to form a bight and diverging towards their other ends, lateral extensions on said other ends of the arms projecting from one and the same side of the latter, the extremities of said extensions having hooks, and an eye intermediate the ends of the arms and disposed between and substantially in the plane of the arms.

6. In a holding device, a member constructed from a single length of wire to provide a pair of arms connected at one of their ends to form a bight and diverging towards their other ends, said other ends of the arms being bent laterally to one and the same side of the arms to form extensions, the extremities of which are bent to provide hooks, and one of said arms being bent upon itself intermediate its ends to form an eye disposed between the arms.

7. In a holding device, a member constructed from a single length of wire bent between its ends into the form of a V, to provide a pair of arms the free ends of which are bent laterally to one and the same side thereof to form extensions having the extremities thereof bent to form hooks, one of the arms being curled upon itself intermediate its ends to provide an eye disposed flatwise between the arms.

8. A holding device comprising a pair of members having spaced apart laterally extending portions engageable with a covering of an ironing board at the opposite said edges of the latter, resilient means normally urging the members towards each other to cause said portions to co-operate in holding the covering in a taut condition on the board, and means on the members to which the resilient relatively large concave portions is slidably connected and rendered shiftable automatically relative to the members to cause the urging action of the resilient means to be exerted equally on all said portions re-

gardless of whether the sides of the board are parallel or relatively inclined, whereby all said portions will be equally effective in their holding action.

5 Signed at Los Angeles, in the county of Los Angeles and State of California this 13th day of March, A. D. 1928.
